UNITED STATES PATENT OFFICE

2,029,910

THREAD FLUID TREATING DEVICE

Henry R. Childs, Kingsport, Tenn., assignor to
 Eastman Kodak Company, Rochester, N. Y., a
 corporation of New York

Application March 6, 1934, Serial No. 714,355

5 Claims. (Cl. 18—8)

This invention relates to devices adapted to apply fluid to threads, filaments, yarn, or the like. One object of my invention is to provide a device for applying fluid to threads which will always carry the right amount of such fluid to a thread contacting with it. Another object of my invention is to provide a fluid applying device in the form of a mesh screen so that the interstices between the wires will, by capillary attraction, conduct the fluid over that area of the screen which may contact with threads or filaments. Another object of my invention is to provide a simple and easily controlled method of conveying fluid to the screen. Still another object 15 of my invention is to provide a fluid applicating device which can be made in any desired width to take care of one or a large number of threads which are being led into a path contacting with the applicator, and other objects will appear from the following specification, the novel features being particularly pointed out in the claims at the end thereof.

Coming now to the drawing wherein like reference characters denote like parts throughout:

25 Fig. 1 is a fragmentary view of a portion of an artificial silk spinning cabinet equipped with a thread lubricating device constructed in accordance with and embodying a preferred form of my invention.

30 Fig. 2 is a fragmentary front plan view of the device shown in Fig. 1.

Fig. 3 is an enlarged sectional view on line 3—3 of Fig. 1, but with the supply tank and pipes omitted.

35 This invention is particularly adapted for use in applying a liquid to a thread, and is especially useful for the application of conditioning oil to artificial silk filaments such as are produced by the dry spinning method.

40 It is desirable to have such delicate threads or filaments contact with as few parts of the machine as possible, and where the filaments pass around guides, it is desirable to have the contact with the guides short.

45 I have found that a smooth, satisfactory guide and fluid applicator for thread can be made by utilizing a wire-mesh screen in which the individual wires which make up the screen are smoothly rounded as such a screen forms an entirely satisfactory contacting surface for the delicate filaments.

The mesh of such a screen naturally varies with the desired results. If considerable material is to be applied, a coarser screen may be used, or if less fluid is to be applied to the thread, the screen

may be made finer. I have found that a 350-mesh wire screen is entirely suitable for the ordinary artificial silk filaments, but it is to be understood that this size of screen is given purely by way of example and may be varied at will to suit the particular case in hand.

Such a fluid treating device may be, of course, used for tinting, dyeing, or lubricating thread or, in fact, for applying any fluid to thread.

In accordance with Fig. 1, I have illustrated my invention as applied to a dry spinning cabinet which is indicated broadly as 1 and as having a nozzle 2 through which the filaments 3 are extruded in the usual manner. These filaments may be drawn across my fluid treating device designated broadly as 4 and may pass from the cabinet through an opening 5 after which the filaments may pass to a winding mechanism from a guide 6.

It might be noted that the operation of dry spinning requires a lower guide over which the filaments are drawn so as to pass at an angle from the cabinet. By applying my fluid treatment operation at this point, it eliminates one guide and does not make necessary any greater contact of the yarn with the guide.

Referring to the drawing, I prefer to construct my fluid treatment device of a wire mesh screen 7 which may be of considerable width and which is preferably formed in an endless band supported at one end by a pipe 8 and at the other end by a wire guide 9. The pipe and the wire guide may be supported by a suitable frame 10 preferably carried by the side of the spinning cabinet 1.

The pipe 8 not only serves to support the upper end of the screen 7, but also provides a means for conducting the thread treating fluid to the screen. The pipe 8, as best shown in Fig. 2, is provided with a valve 11 which controls the flow of fluid into the pipe 8 through the pipe 12 which leads to a supply tank 13. The valve 11 can be readily adjusted to deliver the desired quantity of fluid necessary for the operation of the machine.

The pipe 8 is provided with one or more perforations 14 through which the fluid 15 is admitted to the wire screen 7. Since the wire screen 7 is composed of wires each substantially round in cross section and woven back and forth, there are a plurality of interstices between these wires which will receive the fluid 15. Moreover, the fluid will flow through these interstices by gravity and capillary attraction and will thus conduct the fluid down to the point where it may be absorbed by the filaments.

- Thus, in Fig. 3 the fluid 15 passes through the opening 14 and may flow down the wire mesh screen 7 so that it will pass about the wire supporting rod 9. Consequently, the filaments 3 which contact with a small area of the wire 7 as it passes about the rod 9 absorb the fluid from the meshes of the wire screen. By adjusting the valve 11, the flow of fluid can be readily controlled.
- 10 If desired, the wire screen 7 may be made of sufficient width to take care of a series of different spinning heads as the meshes of the wire by capillary attraction deliver a very even flow of fluid to the contact point.
- 15 I have found that it is preferable to arrange the individual wires 17 of the screen so that the wires passing in both directions will be at an angle to the filaments 3 and preferably so that they will both be at an equal angle. The reason 20 for this is that the filaments will then have equal contacts with the various wires making up the screen and the fluid will be applied and gently rubbed into the filaments as they pass about the rod 9.
- 25 I also believe that such an arrangement of the wires causes the fluid to flow more evenly over all parts of the screen, although satisfactory results can be obtained with the wires running parallel to the filaments.
- 30 As the filaments are drawn around the wire screen 7 as it passes around the rod 9, a certain amount of the fluid is removed, but as fast as a small area of the wire screen becomes undersaturated with fluid, the capillary attraction of 35 the screen for the fluid quickly fills in the meshes of the screen so that a very even supply of fluid is delivered.
- 40 While I have described my fluid applying mechanism as being applied to the spinning cabinet of a dry spinning machine, it is very obvious that such a device can be placed anywhere and may be used in connection with any machine which requires thread guides. It is possible, of course, to make a machine, the sole function of which 45 is to lubricate, dye, or otherwise treat threads or filaments, but it is usually desirable to eliminate such an extra operation and to apply the fluid to the thread as it passes through a machine such as a dry spinning, a rewinding or twisting 50 machine, or the like.

What I claim as new and desire to secure by Letters Patent of the United States is:

1. In a machine for fluid treating thread, a wire mesh screen, means for guiding thread into contact with a portion of said screen, and means for filling the interstices of the screen with a thread treating fluid.

2. In a machine for fluid treating thread, a wire mesh screen, means for guiding thread into contact with a portion of said screen, and means for filling the interstices of the screen with a thread treating fluid, the wires of said screen being positioned at an angle to the path of the thread.

3. A fluid treating device for threads or the like, comprising a feed pipe, a wire guide, a wire mesh screen passing around said guide, a fluid 15 feed pipe, said screen also passing around said feed pipe, means for passing fluid from said pipe to said screen to fill the meshes thereof, and means for guiding thread into contact with the screen near the wire guide to receive fluid there- 20 from.

4. A fluid treating device for threads or the like, comprising an endless wire mesh screen, two supports for the screen including a perforated pipe and a wire supporting rod parallel 25 to the pipe and spaced apart, said endless wire mesh screen passing around the perforated pipe and rod and covering the perforation in the feeding pipe whereby said screen may receive fluid therefrom, a guiding means for directing a 30 thread into contact with a portion of said screen to receive fluid therefrom, the individual wires in said screen being positioned at the contact point with the thread in non-parallel relation to the thread.

5. A fluid treating device for threads or the like, comprising an endless wire mesh screen, two supports for the screen including a perforated feed pipe and a wire supporting rod parallel thereto, said feed pipe being located above the 40 supporting rod, said wire mesh screen covering said perforation in said feed pipe and being adapted to receive fluid therefrom, a guiding means for directing a thread into contact with a portion of said screen to receive fluid there- 45 from, the fluid passing from the perforated fluid pipe and being adapted to flow down through the interstices of said screen by gravity whereby the fluid removed by the thread may be automatically replaced.

HENRY R. CHILDS.
